(57) **CLAIM**

The ornamental design for a decorative rear-view mirror band, as shown and described.

DESCRIPTION

FIG. 1 is a front view illustrating my design for a decorative rear-view mirror band.

FIG. 2 is a left side view thereof.

FIG. 3 is a right side view thereof.

FIG. 4 is a perspective view thereof.

FIG. 5 is a rear view thereof.

FIG. 6 is a top view thereof.

FIG. 7 is a bottom view thereof.

FIG. 8 is a front view illustrating the decorative rear-view mirror band wrapped around a mirror.

FIG. 9 is a perspective view thereof.

FIG. 10 is a front view illustrating another embodiment of the decorative rear-view mirror band; and,

FIG. 11 is a perspective view thereof.

The broken lines shown in FIGS. 1, 2, 3, 4, 6, 7, 8, 9, 10 and 11 are for illustrative purposes only and form no part of the claimed design.
